UNITED STATES PATENT OFFICE.

OLE P. OVERLIEN, OF BLACK RIVER FALLS, WISCONSIN.

GARAGE-DOOR-HOLDER DEVICE.

Application filed June 17, 1922. Serial No. 569,674.

To all whom it may concern:

Be it known that I, OLE P. OVERLIEN, a citizen of the United States, and resident of Black River Falls, in the county of Jackson 5 and State of Wisconsin, have invented certain new and useful Improvements in Garage-Door-Holder Devices; and I do hereby declare that the following is a full, clear, and exact description thereof.

10 My invention relates to a new and improved device for holding garage doors and the like in open position and is particularly adapted for use in connection with double doors that swing outwardly.

15 The general object of the invention is to provide a device which may be attached to the doors on the inner side thereof and which will permit the doors to swing outwardly and will automatically lock the 20 doors when they have reached their open position.

With the above object in view the preferred form of my invention is illustrated in the accompanying drawing in which—

25 Figure 1 is a sectional plan view through the doors with my invention applied thereto, the doors being shown in open position.

Figure 2 is a view similar to Figure 1 but showing the doors in closed position.

30 Figure 3 is a detailed sectional view on the line 3—3 of Figure 1 and showing the locking means, and

Figure 4 is a view similar to Figure 3, but showing a modification thereof.

35 In the drawing the invention is shown as applied to the doors 1 and 2 which are hinged to swing outwardly. Brackets 3 and 4 are provided which are adapted to be secured to the inner faces of the respective 40 doors near their hinged sides. These brackets are connected by a rod which preferably consists of two telescoping sections 5 and 6 which are adjustably secured by the set screw 7 or the like so as to be of the proper 45 length according to the width of the doors to which the device is applied. This rod is pivoted at one end to one of the brackets as shown at 8 a number of holes 8^a being provided for this purpose. A collar 9 is secured to the rod near the other end and is swiveled to the other bracket. The rod projects beyond the collar 9 as shown at 10 and this projecting end cooperates with a spring catch 11 to lock the doors when they are 55 swung open.

The latch 11 is fulcrumed at 12 in a keeper 13 which may be secured in any suitable manner to one side of the bracket 3. The latch is provided with an inclined surface 14 which rides up on the projecting end 10 as the doors are swung open. The projecting end first strikes the stop lug 21 and then engages behind the shoulder 15 to lock the doors against closing. The catch is provided with any suitable spring device for yieldingly holding it in its locking position. In the present instance this device consists of a spindle 16 secured to the catch and provided with a coil spring 17 which urges the latch into position to engage the projecting end of the rod. The catch is provided on the opposite side of its fulcrum with an adjustable end 18 which is offset toward the door and provided with a pendant chain 20 or the like for releasing the catch when it is desired to close the doors. A spring 22 may be provided to connect the bracket 4 with the door jamb to assist in closing the doors.

In opening and closing the doors the rod 5, 6 remains of constant length. As will be seen in Figure 1 when the door 1 is swung inwardly the pivotal point of the collar 9 will swing in the arc of a circle about the door hinge. This will cause the door 2 initially to swing outwardly through a small arc and subsequently as the door 1 approaches its closed position the door 2 will swing inwardly to the position shown in Figure 2.

Owing to the fact that it is necessary for the door 2 to swing outwardly slightly beyond the position shown in Figure 1 it may sometimes be found more convenient to apply the bracket 3 to the door 2 and the bracket 4 to the door 1. When the device is applied in this manner it will be found convenient to secure the latch to the opposite side of the bracket 3. In this position the projecting end 18 of the latch may be adjusted by means of the set screw 19 so as to bring the chain 20 adjacent the door 2.

It will also be seen that it will be sometimes desirable to adjust the amplitude of the outward swinging movement of the doors to accord with the local conditions and the position in which the garage stands. In order to make it convenient to effect such adjustment the latch 11 may be adjustably connected with the bracket as shown in Fig-

ure 4 by means of the bolt 23 which extends thru a slot 24 in the bracket, the spindle 16 being slidably connected with the latch.

It will also be understood that various 5 other modifications may be made which fall within the scope of the appended claims.

I claim as my invention:—

1. In a device of the character described, a pair of brackets adapted to be secured to the 10 inner sides of a pair of outwardly swinging doors, a rod adjustable in length and having one extremity pivoted to one of the brackets, said rod being pivoted near its other end to the other bracket but projecting beyond said 15 last named pivot, a spring catch engageable with said projecting end to lock the same when the doors are opened and means secured to the catch and extending to a point adjacent the door for releasing said catch.

- 20 2. In a device of the character described,

a pair of brackets adapted to be secured to the inner sides of a pair of outwardly swinging doors, a rod having pivotal connection with each of the brackets and projecting at one end beyond its pivot, a keeper secured 25 to the bracket at one side of the projecting end, a latch fulcrumed in said keeper, a spring connected with the latch at one side of its fulcrum and urging said latch to engage the projecting end when the doors are 30 opened and means secured to the latch on the opposite side of its fulcrum for releasing the projecting end, said means being angularly adjustable for the purpose set forth.

In testimony that I claim the foregoing I 35 have hereunto set my hand at Milwaukee, in the county of Milwaukee and State of Wisconsin.

OLE P. OVERLIEN.
